UNITED STATES PATENT OFFICE

LUTHER C. BALDWIN, DECEASED, LATE OF PROVIDENCE, RHODE ISLAND, BY RHODE ISLAND HOSPITAL TRUST COMPANY, ADMINISTRATOR, OF PROVIDENCE, RHODE ISLAND, ASSIGNOR TO U. S. BOBBIN & SHUTTLE COMPANY 1929, OF PROVIDENCE, RHODE ISLAND, A CORPORATION OF RHODE ISLAND

SHUTTLE

Application filed October 9, 1930. Serial No. 487,554.

This invention relates to what are known in the trade as take up devices for shuttles.

The purpose of such devices is to take up the slack of the thread at certain stages of the movements of the shuttle through the warp, and especially if the shuttle rebounds.

It is known that various kinds of take up tensions have been provided for what are known as hand threading shuttles or suction shuttles, but such devices are not adapted for the automatic shuttle to which this device applies.

The problem with the automatic shuttle is to provide a device of such character that it will not prevent the thread from threading.

It is also known that take up members having fingers or arms of various types which move between stationary guides or fingers have been used and tried and that the movement of such take up members has been from side to side and also up and down, but it is believed that this is the first instance a take up member is provided which can move up and down and which is normally held by a spring in the up position whereby on the first pick the tendency of the thread is to force this member down.

The friction member must take hold quickly to prevent ballooning and coils of thread from springing off and must overcome the resistance of the take up member, so that slack thread will be pulled back in through the shuttle eye and not forward from the bobbin.

It is also believed that this is the first instance in an automatic shuttle that a vertically movable take up device of this type, or of any other type with a friction member behind it of such character that the thread will immediately enter the mouth of such friction member as soon as the shuttle begins to move on the first pick thereby creating a sufficient tension on the thread to overcome the force of the spring which operates the take up member and cause the thread to go down on the first pick under the nose of the shuttle block in position to be threaded on the second pick.

With take up devices for hand threaders

such as shown in patents to Canova, #1,458,639 of June 12, 1923; Gloor, #1,409,705 of March 14, 1922; Pavia, #1,439,322 of Dec. 19, 1922 and others, no such friction device is necessary, as the take up is moved by hand to catch the thread. Such a friction member is not as necessary with a take up device for automatic shuttles which move sideways, such as is shown in patents to Rubin, #1,661,308 of March 6, 1928 and #1,770,947 of July 22, 1930, Verdegem et al, #1,704,309 of March 5, 1929.

While there may be other types of friction devices or what are known in the trade as "drag tensions", it is claimed that this is the first time such a device which is located near the front end of the bobbin chamber, at the rear of the shuttle block and take up device and which has a mouth open at the top and in the path of the yarn as it unwinds from the bobbin and which connects with a friction throat formed by guide and friction members which extend from the mouth down and in a tangential direction to said path has been made.

With such a construction, the unwinding thread is instantly caught and there is no tendency thereafter to escape.

In the drawings, Fig. 1 is a plan view of a shuttle with the preferred form of the device in place.

Fig. 2 is a vertical section on the line 2—2 of Fig. 1 viewed from the direction of the arrow, the fur, however, being omitted for clearness.

Fig. 3 is a view similar to Fig. 2, but showing the moving parts in a different position.

Fig. 4 is an enlarged vertical sectional view on line 4—4 of Fig. 2 viewed from the direction of the arrow.

Fig. 5 is an enlarged detail view of the take up member spring and cooperating parts.

Fig. 6 is an enlarged vertical sectional view taken on the line 6—6 of Fig. 2 viewed from the direction of the arrow.

Fig. 7 is a view similar to Fig. 6 of a modification.

Fig. 8 is a view similar to Fig. 6 of another modification.

Fig. 9 is a plan view of a modified type of

take up member parts being broken away for clearness.

Fig. 10 is a fragmentary vertical sectional view on the line 10—10 of Fig. 9 viewed from the direction of the arrow and with the friction device H removed.

Fig. 11 is a plan view of another modification.

Fig. 12 is a bottom view of shuttle block 90. 10 Fig. 13 is a back elevation of friction member H.

In the drawings, S represents a shuttle as a whole including the wooden part 1, metal tip 2 and the metal shuttle block sometimes 15 called the eye or threadder 3.

10 represents the bobbin chamber in the wood which extends up to the threading chamber 11.

20 The wood at 4 is cut away to form a recess to receive the shuttle block 3 which has a side wall 35 on the side of the shuttle eye 13 and a bottom wall 36.

25 These together with the wall 6 of recess 4 form a continuation 7 or part of threading chamber 11 which is continued out in front of block 3 as far as tip 2.

30 An eye slot 12 extends back in the wood from the forward part of threading chamber 11 diagonally back to the eye 13 in the wood in the side of the shuttle.

35 While as shown the shuttle block 3 has a bottom wall 36' and side wall 35, its main purpose is to provide the thread directing guide plate 20 which extends flush with the wooden top of the shuttle down and over at 21 into the threading chamber and thence extends forward and terminates in a nose 22 at the top front end.

40 It slopes over and back diagonally at 26 to form one wall of the eye slot to guide the thread T down around the well known type of horn 23 and over and out the shuttle eye 13 on the second pick.

45 This horn 23 slopes down and back almost touching the front edge of the base 36' of block 3 and then extends up and forms a circular passage 27 through which the thread passes after extending around thread pin 28, as shown in Fig. 3.

50 From the under side 34 of guide plate 20 and extending out from the side 35 next the shuttle eye are a plurality, shown as three, fins 30, 30, 30. These extend down, preferably diagonally forward, to a line which is 55 slightly above the upper part of hole 27 and above the point 29 at the bottom of horn 23 so that when the thread T is drawn down as it unwinds from the bobbin B in bobbin recess 10, it can go down under the bottom edges 36, 36, 36 of these fins 30, 30, 30.

60 Preferably at the free ends of the bottom edges there are downwardly extending tips 37, 37, 37 whereby when the thread once gets underneath them it remains there.

65 A represents a take up member pivoted at

40 on a horizontal pivot 41 which is near the back of the threading chamber and, as shown, is in the back of block 3.

70 This take up member A has a forward guide fin 45 which guides it in slot 57 in block 3 in such manner as to limit its sidewise movement. A tail 46 limits the upward movement of take up A.

75 Take up member A has a side bar 42 from the lower edge 48 of which extend the arms 43, 43, 43, 43 horizontally under the bottom edge 34 of guide plate 20 towards the eye side of the shuttle between the fins 30, 30, 30.

80 Preferably the side bar 42 extends parallel with and proximate the inside wall 6 of the threading chamber and extends up a little above the adjoining ends of arms 43 as shown in Fig. 4.

85 The free ends of arms 43, 43, 43, 43 are bent up at 44, 44, 44, 44 whereby when the thread T gets down under the bottom edges 36 and tips 37, it will stay in place between 48 and the ends 44.

90 In a recess 54 in the back bottom part of block 3 is a compression spring 55 which is 95 adjusted by means of a screw 53.

95 This spring presses up against the under-side of take up member A, under 45 and tends to keep the front end of this member with its arms in the up position.

100 It is preferred to use in connection with this take up device, a drag tension of the type shown at F which is in position directly behind block 3.

105 As shown this drag tension can be dropped in between the slots 16 and 17 and preferably is of the diagonal type whereby the thread will enter an open mouth 68 at the top in the path of the thread unwinding from the bobbin B. This mouth is formed by the lip 65 which extends up diagonally from guide 64 and the upper end of the spring pressed friction plate guide member 67.

110 This guide 64 as shown, is fixed and is integral with the body of the tension member which has the front side 60, back side 61 and sides 62 and 63.

115 160 represents the top diagonal edges of the back and front 61 and 60 and between these edges and the guide 64 is the movable friction plate 67 having sides 168 which extend down on each side of the back and front 60 and 61.

120 A spring 71 starts at 74 and is bent around a pivot 70 and from thence extends up under plate 67 at 75 thence down and through a hole 69 therein and a hole 66 in the part 64 as a tail 76.

125 This spring tends to press the friction plate 67 up against the under side of the friction guide 64 and as the thread is instantly caught in the open mouth and as preferably these two parts extend down and in a direction tangential to that in which the thread unwinds from the bobbin B, as shown in Figs. 130

1 and 2, there is very little danger of thread flying off in coils or ballooning. The thread is instantly caught and firmly held between the battery and the tension member while 5 threading as soon as it starts to unwind.

When, however, there is any slack between the selvage of the cloth and the tension member, it is taken up by the take up member.

It is very necessary that friction should be 10 instantly applied to the thread on the first pick in order that the thread should quickly force the take up member A down far enough to get under nose 22. When once under this nose, it remains there until the second pick 15 when it is pulled down under horn 23.

Instead of any kind of mechanical friction, as shown in Fig. 8, there can be used in a recess 80 in the wood 1 of the shuttle two curved diagonal friction guide plates 84 and 20 85 each faced with a strip of felt 81 or 82. These parts are so formed that the top part 83 of the recess 80 forms an open mouth connecting with the throat formed by the guide plates 84 and 85 and the pieces of felt 80 25 and 81.

Instead of a diagonal drag tension device such as just described, as see Fig. 7, I can use behind the take up, a friction device similar to what is shown in patent to Verde- 30 gem et al. on Shuttle, Mar. 5, 1929, #1,704,309, consisting of the two movable friction plates 171, 171 held in a holder 170 and pressed together by springs 172.

In Figs. 9, 10, 12 and 13, a modification is 35 shown of the construction in which S represents the shuttle and 90 the shuttle block the top part of which 91 forms a thread directing guide plate which extends from the top of the shuttle on the side of the eye 13 over and 40 down into the threading chamber and which terminates in a nose 92 at the top front end from which the usual horn similar to 23 slopes down and back.

The fins which extend down from and over 45 the guide plate on the side of the shuttle eye in this case, however, are made of wire 94, 94, 94 one end of each being inserted into a suitable hole 96 in guide plate 91 and the other end being inserted in a similar hole 95 in the 50 inner side of block 90.

The take up member indicated by 98 is pivoted on a horizontal pin 101 near the back of the threading chamber and a plurality of thread supporting arms 97, 97, 97, 97 normally extend horizontally between the fins 94, 55 94, 94.

Take up member 98, as shown, is coiled at 100 about pin 101 and extends down as a tail 102.

60 As shown in Fig. 12, a rubber band 103 between tail 102 and a pin 104 provides the elastic means to keep the member 98 normally raised.

H is a friction member partly integral 65 with shuttle block 90. It has an open mouth

at 120 which connects with a diagonal throat formed between friction guides 121 and 122.

Guide 121 is a plate similar to 168 and is normally pressed against guide 122 by a spring 123.

While a diagonal open mouthed friction device or drag tension such as shown in Figs. 1, 2, 3, 6, 8 and 13 causes the take up to work better, it is possible as shown in Fig. 7, to use other types of friction devices or to omit all friction devices except perhaps some fur R such as shown in Fig. 11. In such case, however, it is preferable to use only a single thread supporting arm 143 on the take up member K which otherwise is the same as A.

A take up member with a single arm can be made much lighter and a weaker spring can be used. It is useful with weak thread.

What is claimed is:

1. The combination in a shuttle for automatic looms having a bobbin chamber from which there extends forward a threading chamber from which an eye slot extends back to an eye in the side of the shuttle; of a thread directing guide plate which extends from the top of the shuttle on the eye side over and down into the threading chamber and which terminates in a nose at the top front end and from which a horn slopes down and back; a plurality of fins which extend down from under the guide plate on the side of the shuttle eye and which have substantially horizontal bottom edges the ends of which terminate in downwardly extending tips; a take up member pivoted on a horizontal pivot near the back of the threading chamber, said member including a side bar from the lower edge of which a plurality of thread supporting arms extend horizontally under the edge of the guide plate towards the eye side of the shuttle between said fins, said side bar extending parallel with and proximate the inside wall of the threading chamber and projecting above the fingers, the free ends of said fingers being bent up; an adjustable compression spring which presses up against the underside of the take up member near its pivot; and a friction device positioned in front of the bobbin chamber having a mouth open at the top and in the path of the yarn as it unwinds from the bobbin, said mouth connecting with a throat formed by two friction guide members, the adjoining surfaces of which extend down and in a direction tangential to said path, one of said guide members being spring pressed towards the other.

2. The combination in a shuttle for automatic looms having a bobbin chamber from which there extends forward a threading chamber from which an eye slot extends back to an eye in the side of the shuttle; of a thread directing guide plate which extends from the top of the shuttle on the eye side over and down into the threading chamber

and which terminates in a nose at the top front end and from which a horn slopes down and back; a plurality of fins which extend down from under the guide plate on the side 5 of the shuttle eye and which have substantially horizontal bottom edges; a take up member pivoted on a horizontal pivot near the back of the threading chamber, said member including a side bar from the lower 10 edge of which a plurality of thread supporting arms extend horizontally under the edge of the guide plate towards the eye side of the shuttle between said fins, said side bar extending proximate the inside wall of the threading 15 chamber, the free ends of said fingers being bent up; an adjustable compression spring which presses up against the underside of the take up member near its pivot; and a friction device positioned in front of 20 the bobbin chamber having a mouth open at the top and in the path of the yarn as it unwinds from the bobbin, said mouth connecting with a throat formed by two friction guide members, the adjoining surfaces of 25 which extend down and in a direction tangential to said path.

3. The combination in a shuttle for automatic looms having a bobbin chamber from which there extends forward a threading 30 chamber from which an eye slot extends back to an eye in the side of the shuttle; of a thread directing guide plate which extends from the top of the shuttle on the eye side over and down into the threading chamber 35 and which terminates in a nose at the top front end and from which a horn slopes down and back; a plurality of fins which extend down from under the guide plate on the side of the shuttle eye and which have substantially horizontal bottom edges the ends of 40 which terminate in downwardly extending tips; a take up member pivoted on a horizontal pivot near the back of the threading chamber, said member including a side bar from the lower edge of which a plurality of thread supporting arms extend horizontally under the edge of the guide plate towards the eye side of the shuttle between said fins, said side bar extending parallel with and 45 proximate the inside wall of the threading chamber and projecting above the fingers, the free ends of said fingers being bent up; an adjustable compression spring which presses up against the underside of the take up member near its pivot; and a friction device having a mouth open at the top located between the take up member and the bobbin chamber. 55

4. The combination in a shuttle for automatic looms having a bobbin chamber from 60 which there extends forward a threading chamber from which an eye slot extends back to an eye in the side of the shuttle; of a thread directing guide plate which extends from the top of the shuttle on the eye side over and down into the threading chamber 65

and which terminates in a nose at the top front end and from which a horn slopes down and back; a plurality of fins which extend down from under the guide plate on the side of the shuttle eye and which have substantially horizontal bottom edges the ends of which terminate in downwardly extending tips; a take up member pivoted on a horizontal pivot near the back of the threading chamber, said member including a plurality of thread supporting arms which normally extend horizontally between said fins; an adjustable spring which normally tends to raise said take up member; and a friction device located behind said take up member. 70

5. In an automatic shuttle having a thread directing guide plate which extends from the top of the shuttle on the eye side over and down into a threading chamber and which terminates in a nose at the top front end and from which a horn slopes down and back; a fin which extends down from under the guide plate on the side of the shuttle eye and has a substantially horizontal bottom edge; a spring actuated take up member pivoted on a horizontal thread supporting arm which normally extends proximate said fin; and a friction device located behind said take up member. 75
